UNITED STATES PATENT OFFICE.

HENRY FAWCETT, OF KIDDERMINSTER, ENGLAND, ASSIGNOR TO
J. & J. DOBSON, OF PHILADELPHIA, PENNSYLVANIA.

DESIGN FOR A CARPET.

SPECIFICATION forming part of Design No. 18,010, dated January 10, 1888.

Application filed September 28, 1887. Serial No. 230,926. Term of patent 7 years.

To all whom it may concern:

Be it known that I, HENRY FAWCETT, a subject of the Queen of Great Britain, residing at Kidderminster, England, have invented and produced a certain new and original Design for Carpets, of which the following is a full, clear, and exact description, reference being had to the accompanying drawing, forming a part of this specification.

My design is applicable more particularly to loop and cut pile carpets and to those woven with a border. It is illustrated in the drawing as composed of a center or body proper and a double border, the inner one of which is contained with a straight line of C-shaped figures.

I claim—

1. The design for the center or body of the carpet, substantially as shown and described.
2. The design for the border of the carpet, substantially as shown and described.
3. The design for a bordered carpet, consisting of the center and borders, substantially as shown and described.

In testimony whereof I have hereunto affixed my signature this 24th day of May, A. D. 1887.

HENRY FAWCETT.
